UNITED STATES PATENT OFFICE.

BARNET BURSTEIN, OF NEWARK, NEW JERSEY.

DESIGN FOR AN AUTOMOBILE-BODY.

53,654.

Specification for Design.

Patented July 29, 1919.

Application filed April 29, 1919. Serial No. 293,577. Term of patent 14 years.

To all whom it may concern:

Be it known that I, BARNET BURSTEIN, a citizen of the United States, residing at Newark, county of Essex, and State of New Jersey, have invented a new, original, and ornamental Design for Automobile-Bodies, of which the following is a specification, reference being had to the accompanying drawing, forming part thereof.

Figure 1 is a side view of the right hand side of the automobile body.

Fig. 2 is a view of the left hand side of the automobile body, and

Fig. 3 and Fig. 4 are front and rear views, respectively, of my new and ornamental automobile body.

I claim:

The ornamental design for an automobile body, as shown.

BARNET BURSTEIN.
